UNITED STATES PATENT OFFICE.

EDWARD JOHN RIDGWAY, OF STATEN ISLAND, NEW YORK.

DESIGN FOR AN ARTICLE OF MANUFACTURE.

50,703.

Specification for Design.

Patented May 1, 1917.

Application filed December 27, 1916. Serial No. 139,217. Term of patent 7 years.

To all whom it may concern:

Be it known that I, EDWARD JOHN RIDGWAY, a subject of the King of Great Britain and Ireland, residing at Staten Island, in the county of Richmond and State of New York, have invented a new, original, and ornamental Design for an Article of Manufacture, of which the following is a specification, reference being had to the accompanying drawing, forming part thereof.

The figure is a side elevation of a goblet, showing my new design. While the design is primarily intended for goblets, it is ob-

vious that it may be utilized in various articles of manufacture, *e. g.* candle lamps, vases, or similar articles, and I accordingly do not limit my invention to the use of the design in goblets alone.

I claim:—

The ornamental design for an article of manufacture, as shown.

EDWARD JOHN RIDGWAY.
